UNITED STATES PATENT OFFICE

127,305

DESIGN FOR A DICE GAME BOARD

Sydney R. Osterman, Chicago, Ill.

Application January 16, 1941, Serial No. 98,133

Term of patent 7 years

To all whom it may concern:

Be it known that I, Sydney R. Osterman, a citizen of the United States, residing at Chicago, in the county of Cook and State of Illinois, have invented a new, original, and ornamental Design for Dice Game Boards, of which the following is a specification, reference being had to the accompanying drawing, forming part thereof.

Fig. 2 is a side view, looking from the left-hand side of Fig. 1; and

Fig. 3 is a transverse sectional view taken on the lines 3—3 of Fig. 1.

I claim:

The ornamental design for a dice game board, as shown.

SYDNEY R. OSTERMAN.
